UNITED STATES PATENT OFFICE.

JOHN GEORGE REHFUSS, OF PHILADELPHIA, PENNSYLVANIA, ASSIGNOR
TO THE AMERICAN BARREL AND STAVE COMPANY, OF CAMDEN, NEW
JERSEY.

PROCESS OF BENDING BARREL-STAVES.

SPECIFICATION forming part of Letters Patent No. 393,661, dated November 27, 1888.

Application filed March 12, 1888. Serial No. 267,026. (No model.)

To all whom it may concern:

Be it known that I, JOHN GEORGE REHFUSS, a citizen of the United States, and a resident of Philadelphia, Pennsylvania, have 5 invented certain Improvements in the Process of Bending Barrel-Staves, of which the following is a specification.

One object of my invention is to prevent the cracking and straining of staves due to bending of the same prior to their being fed to the setting-up or trussing machine, where a series of staves are secured in barrel form, a further object being to effect the bending of the staves at the same time that they are being fed forward to the machine.

In the accompanying drawings, Figure 1 is a longitudinal section of mechanism which I prefer to use in carrying out my invention; and Figs. 2, 3, 4, and 5 are transverse sectional diagrams on a larger scale on the respective lines 2 2, 3 3, 4 4, and 5 5.

On reference to Figs. 1 and 2, A represents part of a trussing or setting-up machine—that shown being of the construction illustrated 25 and described in an application for patent filed January 24, 1887, Serial No. 225,328—B showing one of the stave-receiving heads having an annular groove, *b*, into which the staves are fed one at a time, and D is the stave feed-way, preferably supported on one of the stringer-bars E of the setting-up machine.

The frame of the stave-feedway has three longitudinal ribs in the present instance—two outer ribs, *d d*, and one central rib, *e*. The 35 outer ribs are of the form shown in Fig. 2, and are provided with overhanging caps carrying a series of anti-friction rollers, *f f*, and on the central rib, *e*, are a series of anti-friction rollers, *g*, the top surface of the rib being 40 inclined from the inlet end *a* to the discharge end *a'*—that is to say, it gradually rises in respect to the side ribs, *d*. Adjacent to each rib *d* is a longitudinal bar, F, one of which is shown in Fig. 1, and each bar has a series of 45 fingers, *i*, which, as the bar is reciprocated, serve to feed the staves in the direction of the arrow, Fig. 1.

The stave is delivered to the feedway at the end *a* in a perfectly flat condition, as shown 50 in Fig. 2; but as the fingers *i* gradually feed the stave forward in the direction of the arrow said stave is bent by the conjoint action of the bars *d* and *e*, and when the stave reaches

the line 3 3 it has assumed the condition shown in Fig. 3, and the bending continues until 55 when the stave reaches the line 4 4 it has assumed the position shown in Fig. 4, and by the time it reaches the line 5 5 it has assumed the condition shown in Fig. 5, it being then 60 preferably bent a little more than is absolutely necessary for the finished barrel. At this point it is fed into the groove *b* of the setting-up machine, and the usual hoops are placed thereon, as described in the aforesaid application.

In some cases I may have longitudinal ribs or bars on each side of the center of the feed-way to bear on the under side of the stave, as shown by dotted lines in Fig. 5, and in place of the friction-rollers on the central bar a 70 plain strip may be used, and friction-rollers may also be placed, as shown in Fig. 5, on each side of the center of the feedway to bear upon the top of the stave, the construction of the bending device varying with the quality and 75 thickness of the staves to be bent. By thus feeding the staves forward in a direction transversely to their length, and at the same time subjecting them to a gradually-increasing pressure, whereby they are bent or curved 80 longitudinally, I am enabled to effect said bending of the stave without that risk of cracking or straining the same which is frequently incurred in bending the staves between dies, and I economize time and space by effecting 85 the bending of the staves simultaneously with the feeding of the same to the trussing or setting-up machine.

The staves may be either hot or cold; but it is preferable in all cases to heat the staves 90 prior to the bending of the same.

I claim as my invention—

The mode described of bending staves, said mode consisting in moving the staves forward in a direction transversely to their length, and 95 while they are being thus traversed subjecting them to a gradually-increasing pressure, whereby they are bent or curved longitudinally, all substantially as specified.

In testimony whereof I have signed my name 100 to this specification in the presence of two subscribing witnesses.

JOHN GEORGE REHFUSS.
